COMBINED PACKAGE AND SPREADER FOR PULVERULENT MATERIAL

William E. Beaumont, Marina del Rey, Calif., assignor to
Downey Fertilizer Company, Downey, Calif., a corpora-
tion of California

Filed Mar. 13, 1968, Ser. No. 10,956

Term of patent 14 years

Int. Cl. D9—04

U.S. Cl. D9—221

FIG. 1 is a front perspective view of a combined package and spreader for pulverulent material showing my new design;

FIG. 2 is a rear elevation thereof on an enlarged scale;

FIG. 3 is a side elevation thereof, the side opposite being identical;

FIG. 4 is a top plan view thereof; and

FIG. 5 is a bottom plan view thereof.

I claim:

The ornamental design for a combined package and spreader for pulverulent material, substantially as shown and described.
